CLAIM

The ornamental design for an electronic device, as shown and described.

DESCRIPTION

FIG. 1 is a top perspective view of a first embodiment of an electronic device;

FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a close-up view of a portion indicated by the circle shown in FIG. 8;

FIG. 10 is a cross-sectional view of the electronic device taken in the direction of line 10-10 of FIG. 3;

FIG. 11 is a top perspective view of a second embodiment of an electronic device;

FIG. 12 is a bottom perspective view thereof;

FIG. 13 is a front view thereof;

FIG. 14 is a back view thereof;

FIG. 15 is a left-side view thereof;

FIG. 16 is a right-side view thereof;

FIG. 17 is a top view thereof; and,

FIG. 18 is a bottom view thereof.

The dashed broken lines depict portions of the electronic device that form no part of the claimed design.

1 Claim, 18 Drawing Sheets
